PRESSING FORM FOR GARMENT SLEEVES

Yervant Amber, Los Angeles, Calif.

Application November 5, 1951, Serial No. 254,861

2 Claims. (Cl. 223—72)

1

This invention belongs in that general class of devices known as presser's auxiliary units in the pressing, cleaning and dyeing establishments and the invention relates particularly to sleeve forms which are employed to expand the sleeve to be steamed and thus pressed without wrinkles and creases. The invention has among its objects the production of a means of the kind described, and similar means, that is simple, durable and compact in structure, inexpensive to make and manufacture, dependable and efficient in use and service, and which is convenient to handle, repair, and maintain in a clean condition and rust-free.

Special construction of the spring holding means of this invention makes it a very simple and easy operation to remove and substitute a new spring covering thereon. Without a suitable covering for the spring, rust and other discoloring matter would soil the garments to be pressed, thus it is important to have a covering that can be easily removed and replaced, a chore not disliked or else the presser would delay too long the replacement of a covering to avoid damage to clothing.

Other objects, advantages and features of this particular invention will appear from a careful perusal of the accompanying drawings, the subjoined and detailed description, the preamble to these specifications, and the claims appended hereto.

Below, applicant describes one of the preferable forms of his invention in order to teach the art thereof and show how to make and use the same, but it is to be understood that the drawings and description thereof are not to limit the invention in any sense whatsoever except as the same may be limited by the prior pertinent art.

In the drawings:

Figure 1 is a perspective view of a sleeve form showing it in a fully expanded condition;

Figure 2 is an end elevational view of the sleeve form;

Figure 3 is a perspective view of the spring employed in the form;

Figure 4 is an elevational view of a portion of the sleeve form; and shown upon an enlarged scale;

Figure 5 is a plan view of that shown in Figure 4.

Old forms now in use do not provide a starting point in which to slip a sweat-proof covering or tube thereon, and it is a great advantage to renew the fabric tubing. Applicant's split

2

spring provides such a starting point and thus presents a better and a more useful article.

The particular form of the invention, as illustrated, has the spaced arm members 1 and 2 which have the general configuration as shown in order to conform with the shape or lines of garment sleeves when placed therein. These members are smooth and free of all impediments which might tend to disturb the inner lining of garment sleeves. The spring is a resilient steel band and consists of three parts which are the long bowed part 5 and the two shorter bowed parts 3 and 4; these shorter parts being hinged to their respective ends of the long part 5 by the pivot pin means indicated at the points 6 and 7. The long bow part 5 has the center hole 8 between the dowel pin holes 9 and 10. The short bow part 3 has a dowel pin hole 11 and a recessed portion or half-hole portion 12 and the other short part has the recessed portion or half-hole portion 13 and the dowel pin hole 14. This division of the band is so made so that the covering material can be easily slipped onto the entire spring band. The covering material may be cotton or of any other suitable fabric in the form of a tube and this is indicated by the reference character 15.

The large bow of the spring band is positioned by the dowel pins 16 and 17 which are firmly fixed into the arm member 1. A metal plate of non-rust material or coating 18 is provided which has aligned holes to receive the dowel pins and a central hole for registration with the hole 8 and sized to receive the wood screw 19. The single wood screw 19 is sufficient when the dowel pins are employed as shown.

A similar non-rust plate 20 is provided for the joint of the two short bands 3 and 4, their respective dowel holes fitting onto the dowel pins 21 and 22 which are firmly secured to the arm 2. A wood screw 23 holds the plate 22 in place. It should now be apparent that the operator need only remove two screws in order to slip the cotton fabric over the band parts.

Although the bands may be of any suitable material and size, it is preferred to make the short bands about 62 thousandths in thickness and the large or long band about 50 thousandths of an inch so that the long band is a bit more elastic than the short bands in order to provide a better balance.

It is, of course, understood that various changes and modifications may be made in the details of form, style, design, materials and construction of the whole or any part of the specifically de-

scribed embodiment of this invention without departing from the spirit thereof; such changes and modifications are considered as being within the scope of the following claims.

I claim:

1. In a sleeve form device for clothes pressing establishments; a pair of elongated arm members having spring attachment means at their central portions, a single composite spring intermediate the arm members and fixed thereto at said means, the spring consisting of an elliptical band which is severed at one of the said means so that the spring can be slipped into a flexible tube, and a single flexible tube covering the band.

2. The sleeve form recited in claim 1 wherein the means consists of a pair of spaced dowel pins anchored in each arm member which pass

through alined holes in the band, a plate having spaced holes which accommodate said dowel pins, and screw means which pass through its respective plate and band portion and into the arm member thereof so as to force its respective band portion tightly against the surface of its arm member.

YERVANT AMBER.
